A. LINARD

ELECTRICAL SWITCH

Filed Jan. 18, 1923

UNITED STATES PATENT OFFICE.

ALEXANDER LINARD, OF MIDDLE BRIGHTON, NEAR MELBOURNE, VICTORIA,
AUSTRALIA.

ELECTRICAL SWITCH.

Application filed January 18, 1923. Serial No. 613,485.

To all whom it may concern:

Be it known that ALEXANDER LINARD, a citizen of the Commonwealth of Australia, and resident of 42 Sussex Street, Middle 5 Brighton, near Melbourne, in the State of Victoria, Commonwealth of Australia, has invented a certain new and useful Improved Electrical Switch, of which the following is a specification.

- 10 This invention relates to an improved electrical switch and has been devised in order to provide a cheap simple and effective switch whereby the light may be dimmed to the smallest degree or gradually strengthened to its greatest intensity.
- 15 The essential features embodied in this invention consist firstly in functioning the switch arm so that it moves over the surface of the resistance winding and directly 20 in contact therewith from the peak of the current to zero and vice versa as desired so that when starting from the peak the light gradually dims and when starting from zero the light gradually strengthens, the arrangement being such that as the switch contact moves from the peak of the current, each winding of the resistance wire causes a decrease in light intensity.

Secondly the formation in the block upon 25 which the wire is wound of one, two or more holes lengthwise of the block and winding to allow air circulation through the winding for cooling the same.

In order that the invention may be more 30 readily understood it will now be described with reference to the accompanying drawings in which:—

Figure 1 is a view in side elevation with the cover in section.

Figure 2 is a vertical central section of Figure 1.

Figure 3 is a view in plan of Figure 1 with the cover removed.

Figure 4 is a view in vertical central section of the block upon which the resistance is wound and its base.

Figure 5 is a view in plan of the winding illustrating by dotted lines the arc or travel of the switch contact over the surface 50 of the winding, and

Figure 6 is a view in plan of an essential detail.

According to this invention a base member *a* is provided preferably circular in shape 55 and recessed at *b* to receive the block *c* upon

which the resistance wire *d* is wound, the block being formed with lugs *e* by means of which it is fastened to the base *a* by the fastening bolts *f*.

The resistance *d* is wound from the peak 60 side *g* of the block *c* and is coupled through the hole *h* to the terminal *h'* connecting the lead *h''*.

The screw *i* connects the other head *i'* and 65 communicates with the conductor arm *j* passing upwardly as at *j'* and then horizontally above the winding *d* as at *j''*.

Held to this arm *j''* by the screw *j''* and sleeve *j'''* is a switch arm *j''''* the outer end 70 of which on the underside is provided with a roller or other contact *j''''* which is adapted to move in the path *j''''* over the surface of the winding *d* shown by dotted lines in Figures 3 and 5.

The radial movement of the arm *j''''* is limited by the stops *j''''* projecting from the end of the arm *j''*, and such radial movement is caused by switch plug or finger piece *k*, countersunk to receive the nut *k'* and pressing on the sleeve *j'''* in direct contact with the 75 switch arm *j''''*, the head *k''* of the screw *j''* being below the arm *j''* so that when the parts are in position the operation of the switch plug or finger piece *k* causes the arm *j''''* to swing radially over the surface of the winding. 80

The winding at the zero side at the end 85 opposite to the peak side *g* is terminated at the dead end which does not communicate with a lead.

In order to cool the winding an air hole or holes *n* of any suitable shape may be formed in the block *c* so that air can circulate through the block and between the 90 windings thereon.

A cover *p* is provided suitably perforated such as at *p'* to allow of air circulation, and this cover is detachably connected to the base *a* in any convenient way, preferably by forming oppositely disposed knobs *p''* on the base *a* which are received in recesses *p'''* formed on the cover. 95

In operation the turning of the switch plug *k* moves the roller *j''''* on switch arm *j''''* over the surface of the winding *d* and when 100 starting from the peak side *g* the further the movement the dimmer the light until it reaches the zero side *l* of the winding.

On the opposite movement the light is 105 gradually strengthened as the roller *j''''* moves 110

towards the peak and as the number of windings d are cut out of the circuit.

I desire it to be understood that various improvements and modifications may be embodied without departing from the spirit and scope of the invention, the essential features of which are above described.

What I claim as my invention and desire to secure by Letters Patent is:—

- 10 1. A device of the character described, comprising, a base, a perforated block on the base, a resistance winding on the block, a U-shaped conductor arm fixed to the base and leading to a point above the winding, a contact arm pivoted to the conductor arm, and a roller on the contact arm in contact with the upper surface of the windings.
- 15 2. A device according to claim 1, an operating knob carried by the upper end of the

conductor arm for operating the contact arm, and a perforated covering casing fixed to the base.

3. A device as described, comprising, a base, a block having a resistance winding wound thereon, the block being formed with holes to allow of the circulation of air between the windings, a fixed conductor arm leading from the base to a point above the winding, a swinging contact arm in electrical contact with the conductor arm, a finger piece for operating the contact arm, and a roller contact on the contact arm positioned to move in contact with the winding over the upper surface thereof.

Signed at Melbourne, Victoria, Australia, 35 this 2nd day of November 1922.

ALEXANDER LINARD.
